UNITED STATES PATENT OFFICE.

GIOVANNI EMANUELE ELIA, OF WASHINGTON, DISTRICT OF COLUMBIA.

PROTECTIVE DEVICE FOR SHIPS.

1,312,841.

Specification of Letters Patent.

Patented Aug. 12, 1919.

Application filed December 22, 1916. Serial No. 138,408.

To all whom it may concern:

Be it known that I, GIOVANNI E. ELIA, a subject of the King of Italy, residing in the city of Washington, District of Columbia, have invented certain new and useful Improvements in Protective Devices for Ships; and I do hereby declare the following to be a full, clear, and exact description of the invention, such as will enable others skilled in the art to which it appertains, to make and use the same.

This invention relates to a protective device for ships, and it is designed for the purpose of protecting the ships against submarine explosions.

An object of the invention resides in the provision of a floating protective device which may be arranged to envelop the ship and lie in contact with the sides thereof, is capable of being towed by the ship, when such conditions exist that its use may advantageously be discontinued, and is capable of being towed by a tug-boat, in conjunction with a plurality of similar devices and boats to inclose and protect an area in which transports or similar ships move.

In the drawings, I have shown an embodiment of my invention, in which drawings:

30 Figure 1 is a plan view of a ship showing the position of the protective device immediately prior to the engagement of the bow of the ship therewith to cause the enveloping of the ship by the device;

35 Fig. 2 is a similar view showing the position of the device after the ship is enveloped thereby;

Fig. 3 is a side elevation of a ship with the device applied thereto;

40 Fig. 4 is a plan view of the device illustrating its position with relation to the ship when it is being towed; and

Fig. 5 is a plan view illustrating the positions of several of the devices when used to 45 inclose and protect an area in which transports or similar ships move.

The embodiment of my invention illustrated in the drawings includes a plurality of protective elements 1, which are substantially rectangular in form and are, in actual practice, approximately twenty-one feet in thickness. These elements are secured together by means of cables 2, which extend from one element to the other and secure 50 them, edge to edge, with sufficient distance 55 between the same to permit the elements to

move individually, both horizontally and vertically, so that the device will accommodate itself to the contours of vessels, and so that the elements may have individual movement, such as may be caused by wave actions. Each of these elements 1 is preferably composed of wood and steel, so arranged that the latter will act as a brace for the former and so that the elements will float in vertical 65 positions. The density of each of the elements is substantially equal to that of the water of flotation, so that when a portion of one of the elements is blown away, the element will float in its original position. 70

In using the device, it is placed in the position disclosed in Fig. 1 of the drawings in substantially the same relation to the ship as disclosed in this figure. When the ship moves forwardly, it will engage the 75 cables between the two intermediate elements, and one section of the protective elements will swing into contact with one side of the ship, while the other section will swing into contact with the other side. This 80 protective device floats in such position that each of the elements will extend at least as low as the bottom of the ship. When the protective device is in the position illustrated in Fig. 2 of the drawings, the sides 85 of the ship will be protected against submarine explosions, as will be obvious.

When, in rough weather, it is desirable to remove the protective device from the sides of the ship, it may be accomplished by 90 merely reversing the direction of the ship until it moves free from the device. After the device has been thus freed from the sides of the ship, it may be attached to the stern thereof, by suitable towing cables, and towed 95 in the manner illustrated in Fig. 4 of the drawings. It is sometimes desirable to convoy a ship or a plurality of ships without attaching the device directly to the ship or ships, and when this condition arises, I contemplate using a plurality of tugboats, 100 which have very slight draft, and, consequently, are practically safe from submarine attacks. Secured to and towed by each of these tug-boats is a protective device similar 105 to that described. The tug-boats operate in the relation to each other disclosed in Fig. 5 of the drawings, so that the protective devices inclose an area in which the ships move, and are, consequently, safe from submarine attacks. 110

From the foregoing description, it will be

seen that I have provided a protective device which is capable of loosely surrounding a ship and lying in contact with the sides thereof, so that it will protect the ship and
5 which may be towed in conjunction with a plurality of other similar devices to inclose and protect an area in which a plurality of ships move, and which is capable of being towed by a ship when it is not desirable to
10 have the same enveloping the ship. Furthermore, I have so constructed the device that the density of the same is substantially equal to that of the water of flotation, and have employed a plurality of elements which
15 are so secured together that they will be free to move individually under the wave actions.

What I claim is:—

A projective device for ships, compris-

ing an elongated body consisting of a series 20 of buoyant elements of substantial and protective thickness extending at least as low on the water as the bottom of the ship and flexibly connected edge to edge to one another for individual movement both vertically and horizontally; whereby said body, on being engaged by the bow of a moving ship, will be caused, solely by the movement of the ship through the water, to fold upon itself into and to maintain a position in contact with and conforming to the curvature of the ship's sides, but will assume a substantially straight-line position when towed through the water by a towing connection attached to one end thereof. 35

In testimony whereof I affix my signature.

GIOVANNI EMANUELE ELIA.
